(57) CLAIM

The ornamental design for a hand held organizer cover plate, as shown and described.

DESCRIPTION

FIG. 1 is a perspective view of a hand held organizer cover plate in full lines with a hand held organizer shown in broken lines representing environmental association matter being for illustrative purposes only and forming no part of the claimed invention.

FIG. 2 is a top plan view of the hand held organizer cover plate.

FIG. 3 is a bottom plan view thereof.

FIG. 4 is a left side elevational view thereof.

FIG. 5 is a right side elevational view thereof.

FIG. 6 is a front elevational view thereof; and,
FIG. 7 is a rear elevational view thereof.
